UNITED STATES PATENT OFFICE.

GEORGE AUGUST SMITH, OF COUNCIL BLUFFS, IOWA.

SNARE-DRUM MUFFLER.

No. 889,053.

Specification of Letters Patent.

Patented May 26, 1908.

Application filed May 24, 1907. Serial No. 375,503.

To all whom it may concern:

Be it known that I, GEORGE AUGUST SMITH, a citizen of the United States, residing at Council Bluffs, in the county of Pottawattamie and State of Iowa, have invented certain new and useful Improvements in Snare-Drum Mufflers; and I do hereby declare the following to be a full, clear, and exact description of the invention, such as will enable others skilled in the art to which it appertains to make and use the same.

This invention relates to improvements in drum snare tensioning devices and mufflers.

The object of the invention is the production of a muffler and snare stretching device which provide means for stretching the snares of the drum, and various adjusting means for adjusting the tension of the snares, together with a cam and cam lever for loosening and again tightening the snares without varying their adjustment.

With these and other objects in view the invention comprises certain novel constructions, combinations and arrangements of parts that will be hereinafter described and claimed.

In the accompanying drawings Figure 1 is a fragmentary sectional view of a drum having secured thereto a muffler constructed according to the present invention, the same being shown in an inoperative or loose position. Fig. 2 is a fragmentary sectional view through a drum with a muffler formed according to the present invention secured thereto and in an operative position. Fig. 3 is a fragmentary top form view of a drum provided with a muffler according to the present invention. Fig. 4 is a section through the muffler detached, on line 4—4 of Fig. 2. Fig. 5 is a detail face view of the snare adjusting device.

In providing snares and tensioning devices therefor it has been found desirable to arrange such devices so as to bring the snares under proper tension and to maintain their tension by the snare holding devices, regardless of whether or not the drum heads are adjusted. Various devices have been provided with varying success, to accomplish this purpose, and it is to this class of devices that the present invention relates.

In providing a device of this character I construct the same with a plate or sustaining member 1 of any desired width, which is designed to be held parallel to the shell of the drum 2 and to have its upper end substan-

tially on the same plane as the upper end of the hoop or band 3 of the drum. In placing the present invention in position I first place a ring or band 4 within the drum at any desired distance from the end thereof, and pass therethrough a bolt 5 and secure the same in position by a nut 6. A suitable washer 7 is preferably rigidly secured to bolt 5 so as to provide means whereby nut 6 may firmly hold bolt 5 in position.

A screw-threaded washer 7' is provided for holding the lower end of member 1 at a proper distance from the shell 2 and a suitable set or lock nut 8 is provided for clamping member 1 against nut 7', and in this manner member 1 is held substantially parallel with shell 2. Member 1 is formed with a slot 9 through which bolt 5 passes so as to permit the member to be adjusted vertically to any desired position. The upper end of member 1 is bent so as to form ears 10 through which a pivotal rivet 11 is designed to pass, for holding in position an arm 12. Arm 12 is formed at one end with an enlarged portion 13, which is designed to accommodate a bolt 14, which is formed with an enlarged portion forming shoulders as 15. Formed on the portion 13 is a tooth or projection 16 which is designed to fit into a corresponding depression in the end or enlarged portion 17 of member 18. The enlarged portion 17 is formed with a passage therethrough that is screw-threaded for receiving the bolt 14, while enlarged portion 18 is formed with a passageway therethrough, but without the screw-threads, so that when the bolt 14 is rotated the same will draw member 17 against member 13 and hold the same firmly in position, tooth 16 preventing any swinging motion after members 13 and 17 have been brought in contact. Formed on the end opposite to member 13 is another enlarged portion 19 which has formed thereon a cam surface 20, which is designed to accommodate a cam arm 22. Cam arm 22 is rigidly secured to or formed integral with a pivotally mounted shaft or member 23, which is designed to pass through member 19. Member 23 is formed with a passageway centrally thereof and which is screw-threaded for receiving the bolt or adjacent member 24. Mounted upon bolt or adjusting member 24 is a lock nut 25 for locking the set screw or bolt 24 in any desired position.

Positioned opposite to bolt 5 is another

securing member or bolt 26, which is designed to sustain a tension member 27. Tension member 27 may be moved upward or downward for varying the tension of 5 snares 28 by reciprocating shaft or member 29. Shaft 29 is held in any desired position by a suitable set screw 30, so as to form a positive securing means for the snares 28. The snares after leaving tension 27 are 10 designed to pass upward and over the head of the drum in any convenient manner, but preferably pass through ring 3. A slot or passageway 31 is provided for the passage of snares 28, and in this way the head of the 15 drum may be tightened or loosened and rim 3 moved without affecting the tension of snares 28. As will be seen from the drawing, the snares 28, after passing from member 27, are designed to contact with the drum 20 head for the full width thereof, and be held in position by member 27.

In operation, after ring 4 and the remaining parts of the muffler have been placed in position the snares 28 are secured to member 25 27 and to member 18, and tightened to any desired extent, and set screw 30 is forced against member 29 for locking the same in position. The snares are preferably adjusted in this manner, but if for any reason 30 the snares are not exactly in the condition desired, set screw 24 may be moved one way or the other, which will either draw member 18 closer to rim 3 or permit the same to be drawn away from rim 3 and consequently 35 vary the tension of the snares. After the snares have been brought under proper tension between the members 18 and 27 they are in condition for operation and will remain in this condition until the various 40 mechanism for bringing the same finally under tension is operated.

It will be observed that none of the tension devices is secured to the drum head or the tightening ring or band of the drum, so that 45 the drum head may be tightened or loosened to any desired extent without in the least affecting the snares. When it is desired to tighten or loosen the drum head, cam lever or arm 22 is rotated so as to permit cam arm 50 22 to take a position at the deepest point in cam surface 19, which will permit member 18 to take the position shown in Fig. 1. The drum head may then be adjusted to any desired tension and after such adjustment cam 55 lever 22 is rotated to the position shown in Fig. 2, and snare 28 will be again brought in contact with the drum head for the entire width thereof. From this it will be observed

that the movement of the cam lever 22 will loosen or tighten snares 28, but will always 60 loosen and tighten the same to the same degree, so that when the snares are tightened by rotating cam 22 to the position shown in Fig. 2 the snares will always be under the tension formerly brought to, without in any 65 way readjusting the same.

What I claim is:

1. A device of the character described comprising a tensioning device, snares secured thereto, snare adjusting means, said 70 means comprising a supporting member, a pivotally mounted member, adjustable snare holding means secured to said pivotally mounted member, a cam for varying the position of said pivotally mounted member, 75 and independent means for varying action of the cam.

2. A device of the character described comprising a drum, a snare tensioning device secured to the shell of said drum, means for 80 varying the position of said tensioning device, snares secured to said tensioning device, and a lever for varying the position of said snares, both the snare adjusting means and snare tensioning means being independent 85 of the hoop of said drum.

3. A device of the character described comprising a drum, snares therefor, means for holding one end of the snares in position, 90 an arm for holding the other end in position, a lever for varying the position of said arm, means for supporting the lever, an enlargement on said lever provided with a cam surface, a sleeve passing through said enlargement, means for supporting said sleeve, and 95 a device contacting with the cam surface for operating the lever.

4. A device of the character described, comprising a drum a snare, means for holding one end of the same in position, independent 100 of the hoop of the drum, an arm for holding the other end in position, a pivotally mounted arm for varying the position of said first-mentioned arm, a plate adjustably secured to the shell of said drum, said plate supporting the second-mentioned arm, and means for varying the position of said second-mentioned arm for moving said first-mentioned arm for bringing said snares into 105 operation.

In testimony whereof I affix my signature in presence of two witnesses.

GEORGE AUGUST SMITH.
